CENTRIFUGAL ACTUATOR APPARATUS
Evereit P. Larsh, 124 E. Monument Ave.,
Dayton, Ohio
Filed July 3, 1963, Ser. No. 292,621
12 Claims. (Cl. 73—538)

This invention relates to control apparatus. The invention relates more particularly to control apparatus associated with rotary mechanism.

This invention is an improvement upon the structure disclosed in my Patent No. 3,058,355.

In various types of rotary apparatus there is a need for control mechanism which functions in accordance with the rate of rotation thereof. For example, an electric motor having a winding which is used only for starting purposes must be provided with means for disconnection of the starting winding after a given rate of rotation has been obtained. Other types of apparatus are also provided with mechanism which operates when a given rate of rotation is obtained.

An object of this invention is to provide positive, snap action control apparatus which operates when a given rotational rate is obtained.

Another object of this invention is to provide such control apparatus which has a minimum number of elements.

Another object of this invention is to provide such control apparatus which can be produced at comparatively low costs.

Another object of this invention is to provide such control apparatus which is durable and long-lived.

Another object of this invention is to provide such control apparatus which can be applied to numerous types of mechanisms for operation of an element thereof.

Another object of this invention is to provide such control apparatus which is capable of performing considerable work as actuation operation occurs at a given rate of rotation thereof.

Another object of this invention is to provide control apparatus which can be used in association with a starting winding of an electric motor to energize and deenergize the starting winding.

Another object of this invention is to provide such control apparatus for an electric motor in which the control apparatus may include a portion of the circuitry or in which the apparatus can be used to operate a switch element.

Other objects and advantages reside in the construction of parts, the combination thereof, the method of manufacture, and the mode of operation, as will become more apparent from the following description.

In the drawing:

FIGURE 1 is an exploded perspective front view showing control apparatus of this invention.

FIGURE 2 is a perspective back view of an actuator member, which is an element of the apparatus of this invention.

FIGURE 3 is a front plan view of apparatus of this invention.

FIGURE 4 is an enlarged sectional view taken substantially on line 4—4 of FIGURE 3.

FIGURE 5 is a sectional view similar to FIGURE 4 but showing elements of the apparatus in another position of operation.

FIGURE 6 is a sectional view, on a slightly smaller scale and with parts broken away, taken substantially on line 6—6 of FIGURE 5.

FIGURE 7 is a back plan view of apparatus of this invention.

Referring to the drawing in detail, control apparatus of this invention comprises a rotor 10 provided with an annular central portion 12.

2

Preferably, the rotor 10 is a thin wall metallic body which is cut and pressed into the desired form and shape. However, any other material or materials may be used and formed in any suitable manner.

The annular central portion 12 has a flange 14 to which is integrally attached a plurality of spaced-apart connector legs 16 which join the central portion 12 to an outer ring 18. The space between each two adjacent legs 16 forms a window in the rotor 10 so that a plurality of windows are provided, as shown in FIGURES 1 and 3.

The outer ring 18 has a front portion 20 and a back portion 22, the portions 20 and 22 being angular one with respect to the other.

A plurality of dent portions or pivot portions 23 are shown formed in the outer ring 18 at the juncture between the portions 20 and 22. The purpose of the dent portions 23 is discussed below.

Encompassing the central portion 12 of the rotor 10 is an annular engagement member 24 having an axial portion 26 and a disc portion 28. Carried by the axial portion 26 are a plurality of spaced-apart spring seat members 30.

The spring seat members 30 are disposed in pairs around the periphery of the axial portion 26 adjacent the disc portion 28. Intermediate each pair of spring seat members 30 but spaced from the disc portion 28 is an abutment portion or cam portion 32. Thus, there are a plurality of abutment or cam portions 32. The spring seat members 30 and the abutment members 32 are rigidly attached to the axial portion 26 by any suitable means such as integrally or otherwise. Each pair of spring seat members 30 and the abutment member 32 disposed therebetween form a group of protuberances on the periphery of the axial portion 26 of the engagement member 24. Each such group of protuberances 30 and 32 are adjacent an opening 34 in the periphery of the axial portion 26 of the engagement member 24.

Within the axial portion 26 and spaced from the disc portion 28 is an inwardly extending rim 36 which is preferably integral with the axial portion 26.

A plurality of actuator members or units 40 are carried by the rotor 10 and by the engagement member 24. Each actuator member 40 includes a weight member or lever member 42 having a base 44. Each weight member 42 is adapted to be disposed within one of the windows formed between adjacent legs 16. Each base 44 has a lug 45 in engagement with one of the abutment members 32.

Carried by the base 44 of each weight member 42 is a resilient arm in the form of a spring 48. The spring 48 may consist of one or more spring wire members. A central portion of the spring 48 is shown rigidly attached by solder or the like to the base 44. A V-shaped tongue portion 50 extends from the base 44. The V-shaped tongue portion 50 is adapted to engage one of the dent portions or pivot portion 23 within the angle formed by the portions 20 and 22 of the outer ring 18, as best shown in FIGURES 4 and 5. Each V-shaped tongue portion 50 straddles one of the dent portions or pivot portions 23. Thus, the tongue portion 50 of each actuator member 40 is pivotal about one of the dent portions 23, as shown in FIGURES 4 and 5.

The wire spring 48 of each actuator member 40 is shown as having a pair of looped portions 52, at opposed portions of the base 44. The opposite ends of each spring 48 are seated in one of the pairs of spring seat members 30 so that each spring 48 is pivotal about a pair of the spring seats 30. Each spring 48 is in compression as each actuator member 40 is pivotally disposed intermediate one of the dent portions 23 and a pair of the spring seats 30, as shown in FIGURES 4 and 5. Thus, each spring 48

urges the rotor 10 and the engagement member 24 axially in directions one from the other.

A hub 60 has a portion 62 which is in firm pressfit relation within the central portion 12 of the rotor 10, as shown in FIGURES 4 and 5. The hub 60 also has a portion 64 provided with an abutment portion or ridge 66 against which the rim 36 is normally in engagement so that the abutment portion 66 limits the axial movement of the engagement member 24 in a direction from the rotor 10.

The outside diameter of the hub 60 is slightly smaller than the inside diameter of the axial portion 26 of the engagement member 24. Therefore, there is a clearance between the hub 60 and the engagement member 24 as balanced forces of the spring members 48 retain the relative positions of the rotor 10 and the engagement member 24, as shown in FIGURES 4 and 5.

FIGURES 5 and 6 show the hub 60 encompassing a shaft 70 for support thereby.

Operation

When the control apparatus of this invention is used in association with an electric motor, a switch or other element of any device (not shown) may have a portion thereof in engagement with the disc portion 28 of the engagement member 24 for operation of the portion with axial movement of the engagement member 24. The engagement member 24 may also be employed as a control element in other uses of the control apparatus of this invention.

The engagement member and other elements of the apparatus are normally positioned as shown in FIGURE 4. The shaft 70 or any other means may be used for rotating the hub 60 and the rotor 10. The engagement member 24 which is connected to the rotor 10 by means of the actuator members 40 also rotates with rotation of the rotor 10.

As the rate of rotation of the rotor 10 and the engagement member 24 increases, centrifugal forces upon the weight members 42 increase and the weight members or lever members 42 tend to move radially outwardly.

As the centrifugal forces upon the weight members 42 increase, the weight members 42 tend to pivotally move about an axis established by the engagement of the V-shaped tongue portion 50 of the actuator member 40 with a pivot portion 23 of the rotor 10.

The spring members or arms 48 continue to resiliently urge the engagement member 24 axially in a direction from the rotor 10.

However, as the rate of rotation of the rotor 10 and the engagement member 24 increases, a condition occurs at which the centrifugal forces acting upon the weight members 42 overcome the resilient forces of the spring members 48. At the instant this condition occurs the weight members 42 move outwardly to a position as shown in FIGURE 5. This causes pivotal movement of each actuator member 40 about its respective pivot portion 23.

As shown and discussed, the looped or end portions 52 of each spring 48 are seated in a pair of the seats 30. Therefore, as the actuator members 40 pivotally move, the spring members 48 thereof change in the general angle thereof from the slope thereof shown in FIGURE 4 to a position slightly inclined from a line normal to the axis of rotation of the rotor, as shown in FIGURE 5. With this change in angle of the spring member 48, there is a change in the direction of force which urges the engagement member 24 from the rotor 10. Due to the fact that the effective length dimension of each spring member decreases only slightly as the angle thereof changes from that shown in FIGURE 4 to that shown in FIGURE 5, the total or effective resiliency of the spring members 48 increases only slightly as the change in angle thereof occurs. Therefore, the change in angle or the

lever action of the spring 48 in its movement from the position thereof shown in FIGURE 4 to the position thereof shown in FIGURE 5, as the spring 48 is seated in the seat 30, urges the engagement member 24 toward the flange 14. The engagement member 24 is so urged by the spring 48 due to the fact that the spring 48 is seated in the seats 30 and the portion of the spring 48 within the seats 30 is moved toward the flange 14 with change in angle of the spring 48 from that shown in FIGURE 4 to that shown in FIGURE 5.

However, the greatest force urging movement of the engagement member 24 toward the rotor 10 occurs from leverage action of the weight member 42 and its lug portion 45. When each of the weight members 42 moves outwardly, the lug portion 45 thereof which is in engagement with the abutment portion 32 moves to the left, which is in a direction substantially parallel to the axis of rotation of the rotor 10, as shown in FIGURE 5. Such movement of the lug portion 45 causes the lug portion 45 to apply leverage action upon the abutment portion 32. The leverage action urges the engagement member 24 axially toward the rotor 10, as shown in FIGURE 5. Thus, each weight member 42 with its lug portion 45 provides lever action upon the engagement member 24 for movement thereof as the weight members 42 move outwardly as a result of centrifugal forces thereupon.

Such change in angle of the resilient forces of the spring members 48 as discussed above provides positive snap action in movement of the engagement member 24 from its position shown in FIGURE 4 to the position thereof shown in FIGURE 5, as the engagement member 24 is moved by the lever action of the weight members 42 and by the change in angle of the spring members 48.

It is to be understood that the lever action of the lug portions 45 upon the abutment portions 32 and the angle change of the springs 48 provide considerable force to axially move the engagement member 24 toward the rotor 10 as the weight members 42 move outwardly as a result of centrifugal forces applied thereto. Therefore, the engagement member 24 may be used to control a load of considerable value as the engagement member 24 axially moves when a given predetermined rate of rotation occurs.

Movement of each weight member 42 from its position as shown in FIGURE 4 to its position as shown in FIGURE 5 is against the resiliency of the spring 48 which is associated therewith. Therefore, when the rate of rotation of the rotor 10 is again reduced below a certain predetermined value, the resilient force of the springs 48 overcomes the centrifugal forces applied to the weight members 42 and the springs 48 acting upon the engagement member 24 move the engagement member 24 in a direction away from the rotor 10. The maximum axial movement of the engagement member 24 in a direction from the rotor 10 is determined by the abutment or ridge 66 of the hub 60. Thus, the engagement member 24 and each weight member 42 are moved to the position thereof as illustrated in FIGURE 4.

Although the preferred embodiment of the device has been described, it will be understood that within the purview of this invention various changes may be made in the forms, details, proportion and arrangement of parts, the combination thereof and mode of operation, which generally stated consist in a device capable of carrying out the objects set forth, as disclosed and defined in the appended claims.

The invention having thus been described, the following is claimed:

1. In control apparatus, a rotor, a plurality of actuator members engaging the rotor and pivotal with respect thereto, an engagement member encompassing the rotor and axially movable with respect to the rotor, the en-

gagement member being provided with a plurality of abutment portions,
each actuator member including substantially coplanar resilient means engaging the engagement member and urging axial movement of the engagement member in a direction from the rotor,
means limiting axial movement of the engagement member in a direction from the rotor,
each actuator member including a weight member, each weight member having an engagement portion which is in engagement with an abutment portion of the engagement member, the engagement portion of each weight member being spaced from the plane of the resilient means of its respective actuator member, each weight member being movable in a direction outwardly from the axis of rotation of the rotor, the engagement portion of each weight member moving toward the rotor with outward movement of the weight member,
centrifugal forces caused by rotation of the rotor causing movement of each weight member in a direction from the axis of rotation of the rotor, such movement of each weight member causing the engagement portion thereof to apply a force to an abutment portion of the engagement member to move the engagement member axially toward the rotor. 20
2. Control apparatus comprising:
a first rotor,
a second rotor,
the rotors revolving about a common axis and being relatively axially movable, one of the rotors encompassing the other rotor,
an actuator member joining the rotors one to the other so that the rotors rotate one with the other, the actuator member engaging one of the rotors at a part thereof spaced from the axis of rotation thereof and engaging the other rotor at a part thereof adjacent the axis of rotation thereof, 30
the actuator member including resilient means urging axial movement of the rotors one from the other, the resilient means having all parts thereof substantially coplanar, the actuator member including weight means movable in a direction outwardly away from the axis of rotation of the rotors, such outward movement of the weight means being caused by centrifugal forces resulting from rotation of the rotors, 35
one of the rotors having an engagement portion, abutment means attached to the weight means and axially movable with outward movement of the weight means, the abutment means being spaced from the plane of the resilient means, the abutment means being engageable with the engagement portion of said rotor to move said rotor axially toward the other rotor when the weight means moves in a direction away from the axis of rotation of the rotors. 40
3. Control apparatus comprising:
a rotor having a hub provided with limit means, the hub being adapted to be attached to a shaft or the like for rotation of the rotor with the shaft, the hub having a radial extension portion, 45
an engagement member encompassing the hub, there being a clearance at all times between the engagement member and the hub, the engagement member being axially movable with respect to the hub and engageable with the limit means of the hub to limit axial movement of the engagement member with respect to the rotor, the engagement member having an engagement portion, 50
a plurality of actuator members, each of the actuator members engaging the extension portion of the hub, each of the actuator members including resilient means in engagement with the engagement member and urging the engagement member toward the limit means of the hub, each of the resilient members having all portions thereof substantially coplanar, 55
60
65
70
75

each actuator member including a weight member, a portion of each weight member being movable outwardly from the axis of rotation of the rotor, each actuator member also having an axially movable portion, the axially movable portion being spaced from the plane of the resilient means, the axially movable portion being engageable with the engagement portion of the engagement member and movable to move the engagement member axially in a direction away from the limit means when the weight member moves outwardly.
4. Control apparatus comprising:
a first rotor, the first rotor having a peripheral rim portion,
a second rotor, the second rotor having a hub portion, the rotors being coaxial and relatively axially movable, one of the rotors encompassing the other rotor but slightly spaced therefrom, actuator means pivotally engaging the rim portion of the first rotor and the hub portion of the second rotor, the actuator means including resilient means urging relative axial movement between the rotors in a direction one from the other, the resilient means having all portions thereof substantially coplanar, the actuator means also including weight means movable in a direction substantially radially with respect to the axis of rotation of the rotors with pivotal movement of the actuator means, the actuator means also including engagement means engageable with one of the rotors, the engagement means being spaced from the plane of the resilient means, the engagement means moving in a direction substantially axially with pivotal movement of the actuator means, such movement of the engagement means causing engagement thereof with said one of the rotors and forcing relative movement of the rotors in an axial direction one with respect to the other.
5. Control apparatus comprising:
a first rotor, the first rotor having a peripheral rim, a second rotor, the second rotor being coaxial with the first rotor and having a hub portion which supports a disc portion and an engagement portion, the second rotor encompassing the first rotor and being axially movable with respect to the first rotor, actuator means pivotally engaging the rim of the first rotor and the hub portion of the second rotor, the actuator means including a plurality of resilient means urging axial movement of the second rotor in a direction from the first rotor, the resilient means having all portions thereof substantially coplanar, means carried by at least one of the rotors limiting axial movement of the second rotor in a direction from the first rotor, the actuator means also including lever means, the lever means having a weight portion movable generally radially outwardly from the axis of rotation of the rotors by centrifugal force as the rotors rotate at a rate greater than a given rate, the lever means also having an abutment portion engageable with the engagement portion of the second rotor, the abutment portion being spaced from the plane of the resilient means, the abutment portion being movable in a direction generally parallel with the axis of rotation of the rotors as the weight portion moves generally radially, said axial movement of the abutment portion causing axial movement of the second rotor as the abutment portion of the lever means moves in engagement with the engagement portion of the second rotor.
6. Control apparatus comprising:
a first rotor,
a second rotor,
the rotors being substantially coaxial and relatively axially movable, means limiting relative axial movement of the rotors, an actuator member intermediate the rotors and in

engagement therewith, the actuator member engaging one of the rotors at a part spaced from the axis of rotation thereof, the actuator member engaging the other rotor at a part thereof adjacent the axis of rotation thereof,

the actuator member including resilient means urging relative axial movement of the rotors one from the other, the resilient means having all portions thereof substantially coplanar,

the actuator member also including lever means pivotally movable by centrifugal forces applied thereto with rotational movement of the rotors above a given rate, the lever means having an engagement portion engageable with one of the rotors urging axial movement thereof as pivotal movement of the lever means occurs, the engagement portion of the lever means being spaced from the plane of the resilient means.

7. Control apparatus according to claim 6 in which the resilient means is in engagement with at least one of the rotors.

8. Control apparatus comprising:

a rotor,
an engagement member adjacent the rotor and rotatable about substantially the same axis of rotation as the rotor,

a plurality of actuator members,

each actuator member including a looped spring wire member, each of the spring wire members having the two ends thereof in pivotal engagement with the engagement member adjacent the axis of rotation thereof, a portion of each actuator member being in pivotal engagement with the rotor at a position spaced from the axis of rotation thereof, the spring wire members normally urging axial movement of the engagement member in a direction from the rotor, each actuator member including a lever member which has a weight portion movable in a direction from the axis of rotation of the rotor by centrifugal forces when the rotor reaches a given predetermined rate of rotation,

each lever member having axially movable force transmission means engageable with the engagement member, the force transmission means being movable axially with movement of the weight portion in a direction from the axis of rotation of the rotor so that the lever member forces the engagement member axially toward the rotor when the weight portion thereof moves in a direction from the axis of rotation of the rotor.

9. Control apparatus comprising:

a first rotor,
a second rotor adjacent the first rotor and rotatable about substantially the same axis as the first rotor, a movable actuator member disposed intermediate the rotors,

the actuator member being in pivotal engagement with both of the rotors,

the actuator member including a wire spring member which is seated within one of the rotors and which normally urges relative movement of the rotors one from the other, the wire spring member having all parts thereof substantially within a given plane,

the actuator member also including a lever member attached to the wire spring member, the lever member having an axially movable engagement portion engageable with one of the rotors for axial movement thereof, the axially movable engagement portion being spaced from the plane of the wire spring member, the lever member also having a weight portion which is movable substantially radially outwardly from the axis of rotation of the rotors, the weight portion being generally radially movable from the axis of rotation of the rotors by centrifugal forces resulting from rotation of the rotors above a given rate so that the axially movable portion of the lever member urges one of the rotors axially as the weight

portion moves radially from the axis of rotation of the rotors, the lever member and the wire spring member being attached together so that movement of the lever member causes movement of the wire spring member so that the wire spring member also urges said one of the rotors to move axially as the wire spring member is moved by movement of the lever member.

10. In control apparatus:

a first rotor,
a second rotor, the rotors being substantially coaxial, the rotors being relatively axially movable, a resilient member intermediate the rotors urging movement of the rotors one from the other, the resilient member being seated within a portion of the second rotor and generally within a plane which is angular with respect to the axis of rotation of the rotors, the rotors rotating one with the other,
a lever member firmly carried by the resilient member so that movement of the lever member causes movement of the resilient member, the lever member having a weight portion which moves radially outwardly as the rotors reach a rotational rate greater than a given value,

the lever member also having a thrust portion which moves in a direction substantially parallel with the axis of rotation of the rotors when the weight portion of the lever member moves radially outwardly, the thrust portion being spaced from the plane of the resilient member and engageable with the second rotor for axial movement thereof toward the first rotor, such outward radial movement of the weight portion of the lever member causing the resilient member to angularly move so that there is a change in angle of the general plane of the resilient member with respect to the axis of rotation of the rotors so that as the resilient member is seated within a portion of the second rotor the second rotor is urged closer to the first rotor, the change in the angle of the resilient member causing a decrease in the dimension of the resilient member from the first rotor to the second rotor so that an increase in compressional forces of the resilient member occurs as the second rotor moves closer to the first rotor, such outward radial movement of the weight member causing axial movement of the thrust member which also urges movement of the second rotor toward the first rotor.

11. Control apparatus comprising:

a first rotor,
a second rotor,
the rotors being substantially coaxial and relatively axially movable,
actuator means in engagement with both of the rotors, the actuator means including resilient means urging relative axial movement between the rotors, the resilient means having all portions thereof substantially within a given plane and angular with respect to the axis of rotation of the rotors,

the actuator means including lever means attached to the resilient means, the lever means being pivotally movable by centrifugal forces applied thereto with rotational movement of the rotors above a given rate,

the lever means having an engagement portion engageable with one of the rotors and urging axial movement thereof as pivotal movement of the lever means occurs, the engagement portion of the lever means being spaced from the plane of the resilient means, pivotal movement of the lever means causing change in the angle of the resilient means with respect to the rotors so that the lever means and the spring means urge relative movement of the rotors one toward the other.

12. Control apparatus comprising:

a first rotor,
a second rotor, the second rotor having a spring seat,

the rotors being substantially coaxial and relatively axially movable,
actuator means intermediate the rotors and in pivotal engagement therewith,
the actuator means including spring means seated in the spring seat of the second rotor, the spring means urging relative axial movement between the rotors, the spring means being substantially within a given plane and being angular with respect to the rotors,
the actuator means including lever means movable angularly by centrifugal forces applied thereto with rotational movement of the rotors in excess of a given rate,
the lever means having a thrust portion engageable with the second rotor urging axial movement thereof toward the first rotor as the lever means moves,
the lever means being attached to the spring means so that the angle of the spring means with respect to the

5

10

15

rotors changes as the lever means moves angularly, angular movement of the spring means thus urging movement of the second rotor toward the first rotor as the spring means is seated in the spring seat of the second rotor, angular movement of the lever means thus causing the thrust portion thereof to urge movement of the second rotor toward the first rotor.
